Primary Examiner — Marianne Pandozzi(74) Attorney, Agent, or Firm — Cozen O'Connor(57) CLAIM

The ornamental design for a lighthouse beverage dispenser, as shown and described.

DESCRIPTION

FIG. 1 is a perspective view of a lighthouse beverage dispenser showing my new design;

FIG. 2 is a front view thereof;

FIG. 3 is a top plan view thereof;

FIG. 4 is a right side view thereof;

FIG. 5 is a left side view thereof;

FIG. 6 is a rear view thereof; and,

FIG. 7 is a bottom plan view thereof.

The broken lines in the drawing depict portions of the lighthouse beverage dispenser that form no part of the claimed design.
